UNITED STATES PATENT OFFICE.

CLINTON MYERS KOONTZ, OF ALLENTOWN, PENNSYLVANIA.

GRINDING AND POLISHING CONE.

1,119,760.

Specification of Letters Patent.

Patented Dec. 1, 1914.

Application filed December 23, 1913. Serial No. 808,335.

To all whom it may concern:

Be it known that I, CLINTON MYERS KOONTZ, a citizen of the United States, residing at Allentown, in the county of Lehigh and State of Pennsylvania, have invented certain new and useful Improvements in Grinding and Polishing Cones; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in what may be termed grinding, abrading, or polishing cones.

The invention has for its object to provide for suitably effecting the grinding or reducing, particularly, of rubber plates after having been vulcanized for dental or other purposes.

A further object is to provide for facility or readiness of manufacture of the grinding or abrading cone.

A still further object is to reduce or minimize the number of parts required in the making of the grinding cone.

A still further object is to render the device highly effective and readily applied for its intended purpose.

A still further object is to carry out the aforesaid ends in a simple and expeditious manner.

The invention therefore consists of certain instrumentalities and features of construction substantially as hereinafter fully disclosed and defined by the appended claims.

In the accompanying drawing is illustrated the preferred embodiment of my invention wherein it will be understood that various changes and modifications of the detailed construction and arrangement of the parts may be made without departing from the spirit of the invention, and in which drawing:

Figure 1 is a perspective view of my improved grinding or reducing cone. Fig. 2 is a central longitudinal section thereof as exemplified for practical use. Fig. 3 is a rear end elevation of the grinding or abrading cone detached from the carrying mandrel therefor. Fig. 4 is a vertical transverse section thereof. Fig. 5 is a plan view of the

abrading strip or blank viewing the adhesive treated surface or side thereof. Fig. 6 is an opposite side view of the same.

In carrying out my invention I suitably provide a mandrel, shaft or carrying member 1 for the grinding or abrading cone 2, said mandrel or carrying member being preferably manually or hand actuated, it being rotatably supported in position in any suitable way, preferably as shown and having a handle or crank 3 at one end. The opposite end of the cone carrying member or shaft 1 is formed with a circular portion or disk 4, the extreme terminal of said shaft 70 or carrying member being provided with a longitudinal slit, split or slot 5 extending inwardly to the disk or circular shoulder 4 for a purpose presently seen.

A grinding or abrading cone 2, as herein employed, is formed from a suitably provided blank 7, generally of sandpaper, with the inner side or surface thereof suitably coated or treated with an adhesive, as glue or the like for effecting adherence between its folds or windings, as will more fully presently appear. The blank 7, as disclosed in Figs. 5 and 6, is produced in general longitudinal strip-outline with a portion of its length adapted by suitably winding or rolling the same upon itself to constitute a double thickness of cylindrical or tubular outline, as at 8, at its normally rear end for the reception of the slotted end portion 5 of the mandrel 1 which rear end rests against the shoulder 4 of the mandrel. The remaining portion of the strip or blank 7, as it is wound upon itself, results in the formation of a hollow cone, as at 9, whereby as the outer end layer or winding of the strip is brought into grinding or abrading engagement or action, by suitably actuating the mandrel with the object, as a vulcanized rubber plate, said end abrading layer will have the effect to suitably reduce or cut away the rubber plate, also to conform by reason of its flexibility to the outline of the surface being ground or reduced as is apparent. It will also be seen that as the winding or layer after layer of the abrading material or sandpaper of the cone is used up the same is readily removable until the entire cone or the windings thereof are utilized, as will be readily appreciated.

In applying the cone forming strip to the mandrel 1 the initial end 10 of said strip is inserted into the slit or slot of the

mandrel and thus retained therein as the mandrel is actuated in forming the strip into the cone, said initial end by reason of the bend thus imparted thereto taking the form of a partition bisecting the bore of the tubular or cylindrical portion 8 of the cone, the windings or layers of the strip resulting from the actuation of the mandrel being simultaneously brought into adhesive contact with each other accordingly completing the formation of the cone. Adhesive material or glue may be also applied to the resulting rear edges of the cone strip windings or layers for further or greater adherence therebetween. An abrading or grinding cone is thus produced which does not require any additional fastening means outside of itself for the retention of its windings or layers one in contact with the other at their rear edges and the cone itself upon its carrying or actuating mandrel as heretofore made necessary, as is thought has been made clearly apparent.

Having thus fully described the invention what I claim as new and desire to secure by Letters Patent is:—

1. A grinding or abrading cone including a tapering strip of material with an

outer abrading surface and an inner adhering surface, said strip being wound upon itself in layers resulting in an internal cone formation, the extreme inner end of the tapered strip lying transverse of the axis of said cone, to enter a bifurcated mandrel, the layers of said cone extending beyond the said transverse end of said strip, substantially as described.

2. In a grinding or abrading contrivance, a tapered cone, forming strip and a mandrel having a bifurcated end with a shoulder adjacent said bifurcation, the slit of said bifurcation receiving the extreme inner end of said tapered strip and forming a bend therein transverse of the axis of said cone. the layers of said cone extending beyond the said transverse bend therein, said strip being wound by the actuation of said mandrel layer upon layer, the resulting contour of said wound strip forming a hollow cone.

In testimony whereof, I affix my signature, in presence of two witnesses.

CLINTON MYERS KOONTZ.
